HYDRAULIC STEADY REST CHUCK

Russell S. Adair, Youngstown, Ohio

Application April 2, 1947, Serial No. 738,995

2 Claims. (Cl. 279—4)

1

This invention relates to steady rests and more particularly to chucks therefor.

The principal object of the invention is the provision of a steady rest chuck.

A further object of the invention is the provision of a hydraulically operated steady rest chuck.

A still further object of the invention is the provision of a hydraulically actuated steady rest chuck capable of imparting uniform motion to the work piece engaging members of the chuck.

A still further object of the invention is the provision of a self-contained hydraulic steady rest chuck.

The invention shown and described herein relates to metal forming machines such as lathes and more particularly to steady rests used in connection therewith for supporting sections of material in operative relation in the said lathe.

It is well known that various forms of steady rest constructions have been proposed and in view of the necessity of positively centering the steady rest work engaging members, with the work so as to hold it in proper location in the machine, many of these proposed constructions have been found inoperative.

In the present invention, a steady rest is disclosed in which the work engaging members are reciprocally mounted and uniformly and simultaneously moved by means of a multiple cam ring with which the several work engaging members are engaged. Hydraulic means is provided for imparting partial rotating movement to the cam ring and the invention resides primarily in the combination of the reciprocally mounted work engaging members, the multiple cam ring with which they register for movement and the hydraulic means for imparting partial rotating movement to the multiple cam ring.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is an end elevation of a portion of a lathe and a hydraulically actuated steady rest chuck positioned thereon.

Figure 2 is an enlarged detailed elevation of

2

the hydraulically actuated steady rest chuck with parts broken away and parts in cross section.

Figure 3 is a side elevation of a pump handle used in actuating a hydraulic steady rest chuck.

By referring to the drawings and Figure 1 in particular, it will be seen that a lathe or similar machine bed is generally indicated by the numeral 10 and that a steady rest supporting frame 11 is slidably positioned thereon and that the steady rest supporting frame 11 is provided with sidewardly movable locking members 12 which are adapted to engage portions of the machine bed 10 to position the steady rest in any desirable location thereon and maintain it in such position. This particular locking means is not further illustrated or described herein, as it constitutes in part the subject matter of my co-pending application, Serial No. 677,033, filed June 15, 1946 on Steady rest for a lathe.

The present invention relates to the chuck or work engaging portions of the steady rest as disclosed in the upper portion of Figure 1, the reciprocally mounted work engaging members being indicated by the numeral 13 and each in turn being provided with a manually adjustable tip portion 14. These reciprocally mounted work engaging members 13 are preferably positioned in a triangular pattern radially spaced about the center point of the work receiving opening 15 of the steady rest, the main circular body portion of which is generally indicated by the numeral 16.

It will be obvious to those skilled in the art that the several work engaging members 13 are uniformly and simultaneously moved into engagement with a work piece positioned therebetween and through the opening 15 in the steady rest body 16 by suitable means so that the work piece will be supported on its true axis. The means for motivating the work engaging member 13 comprises a multiple cam ring, as best shown in Figure 2 of the drawings and by referring thereto it will be seen that the multiple cam ring is indicated by the numeral 17 and that it includes a plurality of cam slots 18 formed in arcuate pattern therein, each of which provides a means when the cam ring 17 is partially rotated, for imparting reciprocal movement to the work engaging members 13 which engage the cam slots 18 by pin means 19.

In order that the cam ring 17 may be rotated partially so as to effectively move the work engaging members 13 inwardly and outwardly of the opening 15 and hence into and out of engagement with a work piece positioned therethrough, hydraulic means for moving

the cam ring 17 with respect to the body member 16 of the steady rest is provided.

The hydraulic means is disclosed in cross section in Figure 2 of the drawings and may be seen to comprise two general interconnected assemblies, one of the assemblies comprising a hydraulic cylinder 20 in which a telescopically arranged piston 21 is operatively positioned, one end of the hydraulic cylinder 20 being pivotally affixed by means of a pivot 22 to the body member 16 of the steady rest and the telescopically arranged piston 21 pivotally affixed to the cam ring 17 by means of a pivot 23. The telescopically arranged piston includes the main cylinder engaging portion 21 and a secondary plunger portion 21A, the plunger portion 21A being slidably mounted in the hollow interior of the piston 21 and an end thereof extending outwardly of the end of the piston 21 for engaging the pivot 23. Thus, hydraulic pressure introduced adjacent the innermost end of the piston 21 and plunger 21A thereof as through a communication channel 24 will move the piston 21 to the right as shown in Figure 2 of the drawings, until its full extension is reached and shoulders 25 thereon engage shoulders 26 formed on the inner wall of the cylinder 20. When this occurs, continued hydraulic pressure introduced into the cylinder 20 through the channel 24 will cause the plunger 21A to move outwardly of the hollow piston 21. This action provides a large degree of motion between the pivots 22 and 23 and thereby effectively imparts suitable movement to the cam ring 17 which is in turn translated to reciprocating movement of the work engaging members 13 by reason of their registry with the cam slots 18 formed in the cam ring 17.

Means for supplying hydraulic pressure to the piston and cylinder assembly just described is provided and comprises a pump of novel formation also located within the body member 16 of the steady rest and capable of manual actuation by the use of a pump handle 26 which is partially shown in operative relation in Figure 2 and is also shown in side elevation in Figure 3. The pump handle is arranged to engage a piston 27 located in a cylinder member 28 disposed in a hollow pump body member 29. The pump body member 29 is affixed to the body member 16 of the chuck by means of shoulders 30 and is of sufficient size to form a reservoir for hydraulic fluid, the chamber defined by the hollow pump body member being indicated by the numeral 31. A drilled and tapped opening 32 provided with a closure plug 33 provides access to the chamber 31 and the pump cylinder 28 will be seen to be disposed within the chamber 31 to that reciprocating movement imparted to the piston 27 in the pump cylinder 28 as by the pump handle 26 will effectively move hydraulic fluid from the chamber 31 to the channel 24. The piston 27 is normally urged outwardly of the pump cylinder 28 by means of a spring 34 and a pair of ball type check valves 35 and 36, respectively control the inlet and outlet openings communicating with the interior of the pump cylinder 28. The ball check 36 is located in one end of a tubular extension 37 of the channel 24 heretofore referred to and the outer end of the tubular member 37 is connected with the channel 24 of the cylinder 20 by means of a section of flexible tubing 38. A pressure gauge 39 is also connected with the channel 24 by means of a section of flexible tubing 40 and is disposed in the periphery of the body member

16 so that the pressure built up by the piston 27 in the pump cylinder 28 may be observed.

It will thus be seen that when the pump handle 26 is engaged with the body member 16 of the steady rest as in a recess therein and the handle moved manually, the piston 27 is moved inwardly of the pump cylinder 28 thereby compressing the spring 34. When the handle 26 is moved away from the piston 27 the spring 34 moves the piston 27 outwardly and fluid from the chamber 31 is drawn into the pump cylinder 28 flowing past the ball check valve 35. When the piston 27 is again moved inwardly of the pump cylinder 28 as by the handle 26, the fluid in the pump cylinder 28 moves past the ball check valve 36 and outwardly through the tubular extension 37, the flexible hose 38 and through the communication channel 24 into the cylinder 20 where it moves the telescopic piston assembly 21. This action increases the effective distance between the pivots 22 and 23 and thereby causes the cam ring 17 to move, which movement is imparted to the work engaging members 13 heretofore referred to. When the work engaging members 13 are thereby moved in the opposite direction, a valve 41 is opened which opens a communication channel 42 which includes a section of flexible tubing 43 and by-passes the hydraulic fluid directly from the cylinder 20 to the chamber 21. A heavy coil spring 44 is connected between the cam ring 17 and the body member 16 and serves to partially rotate the cam ring 17 in the opposite direction thereby telescoping the telescopic piston assembly 21 and moving the hydraulic fluid back into the chamber 31. When this occurs, the work engaging members 13 are moved in the opposite direction by reason of their engagement with the cam slots 18 in the cam ring 17.

It will thus be seen that a hydraulically actuated steady rest chuck has been described and disclosed and it will be seen that it will operate efficiently for its intended purpose and thereby meet the several objects of the invention.

Having thus described my invention, what I claim is:

1. In a steady rest having a plurality of movably mounted work engaging members, means for imparting simultaneous and uniform movement to the said work engaging members, said means including a multiple cam member rotatably positioned in the said steady rest, a spring normally biasing the said multiple cam member in one direction and hydraulically actuated extensible means for moving the said multiple cam member in the opposite direction, said work engaging members in registry with the said multiple cam member, said hydraulically actuated extensible means comprising a fluid reservoir, a fluid pump disposed in said reservoir, a telescopically engaged piston and cylinder connected to the said steady rest and to the said multiple cam member, flexible fluid connection means connecting the said piston and cylinder assembly with the said pump and reservoir, and means on the exterior of the said reservoir through which the pump may be energized.

2. In a steady rest having a plurality of movably mounted work engaging members, means for imparting simultaneous and uniform movement to the said work engaging members, said means including a multiple cam member rotatably positioned in the said steady rest, a spring normally biasing the said multiple cam member in one direction and extensible hydraulically actuated

means for moving the said multiple cam member in the opposite direction, said work engaging members in registry with the said multiple cam member, said extensible hydraulically actuated means comprising a fluid reservoir, a fluid pump disposed in said reservoir, a telescopically engaged piston and cylinder connected to the said steady rest and to the said multiple cam member, flexible fluid connection means connecting the said piston and cylinder assembly with the said pump and reservoir, and means on the exterior of the said reservoir through which the pump may be energized, and fluid pressure gauging means in communication with the flexible fluid connection means.
